UNITED STATES PATENT OFFICE.

NATHAN RUSSELL DAVIS, OF FREETOWN, MASSACHUSETTS.

BARREL-LOCK FOR BREAKDOWN GUNS.

SPECIFICATION forming part of Letters Patent No. 294,772, dated March 11, 1884.

Application filed December 11, 1883. (No model.)

To all whom it may concern:

Be it known that I, NATHAN RUSSELL DAVIS, of Freetown, in the county of Bristol, of the Commonwealth of Massachusetts, have invented 5 a new and useful Improvement in Breech-Loading Fire-Arms; and I do hereby declare the same to be described in the following specification and represented in the accompanying drawing, which is a longitudinal section of 10 parts of a breech-loading fire-arm provided with my invention, such invention being not only to hold retracted the locking-bolt of the barrel or barrels while such barrel or barrels may be raised above the breech for being 15 charged, but to automatically set such bolt free for it to be thrown forward to lock the barrel or barrels down in position for discharge of the charge or charges thereof.

In the drawing, A denotes the stationary 20 breech, and B one of the barrels, of a double-barreled breech-loading gun, such barrels being connected together and pivoted to a projection, C, extending from the breech. The usual pivotal and locking projection of the 25 barrels is shown at D as provided with a recess or notch, a, adapted to receive and co-operate with the slide-bolt E, whose retraction-lever is represented at F. This lever and bolt are to be supposed to be adapted and arranged 30 in the usual manner, and to be provided with a spring for advancing the bolt, the lever being for retracting the bolt or drawing it out of the notch a, in order to allow of the barrels being turned above the breech for being charged. 35 The bolt is recessed lengthwise to receive a latch, G, and its operative spring b. This latch is notched, as shown at c, and the spring is applied so as, when the bolt is drawn back, the latch will be forced upward by the spring to 40 engage the latch with a catch or projection, d, extending down from the breech in manner as shown, such catch being received within the notch c of the latch. On depressing the barrels to close them by the breech, they at their 45 junction or their cartridge-retractor f will be borne down upon the latch and will depress it

out of engagement with the catch d, in which case the spring for advancing the bolt will be free to throw it forward into the notch a. The said spring for advancing the bolt may be applied either to the said bolt or to its operative lever.

From the above it will be seen that without the latch the bolt would be advanced so as to prevent a full depression of the barrels relatively to the breech, and that such full depression could not be effected without first retracting the bolt by manual power applied to its lever, such back movement of the bolt being to allow the locking projection D to pass down 60 clear of the bolt.

I do not claim in a breech-loading fire-arm a catch-bolt and its operative spring arranged below the locking-bolt, such bolt having a stud for the notched locking projection of the barrels to act upon to depress the catch-bolt, all being as shown in the United States Patent No. 213,760. In my improvement the latch G and its actuator-spring are carried by and movable with the locking-bolt, and there is to 65 the breech a catch, d, extending down therefrom to the latch. With my improvement the barrels, when down, are held by both latch and bolt entering the notch a, such latch and bolt constituting a compound bolt.

I claim—

In a breech-loading fire-arm having a stationary breech and a barrel or barrels pivoted or hinged, so as to be movable relatively to such breech, in manner as set forth, the combination of the notched latch G and its actuating-spring b, secured or attached to the bolt E, so as to be movable lengthwise thereby, with the breech A, the barrel or barrels B, the notched locking projection D, and the stationary latching-catch d, such catch being extended from the breech, and all being arranged in manner to operate substantially as set forth.

NATHAN RUSSELL DAVIS.
